STORAGE BATTERY CASE

Robert L. Brown, Milwaukee, Wis., assignor to Globe-Union, Inc., Milwaukee, Wis., a corporation of Delaware

Application May 4, 1953, Serial No. 24,839

Term of patent 14 years

(Cl. D26—6)

FIG. 1

FIG. 3

Fig. 1 is a view in side elevation of a storage battery case, showing my new design;

Fig. 2 is a view in end elevation; and

Fig. 3 is a top plan view.

The dominant features of my design reside in those portions shown in full lines.

I claim:

The ornamental design for a storage battery case as shown and described.
